UNITED STATES PATENT OFFICE.

JOHN F. WAIDELICH, OF LANSING, MICHIGAN.

HEEL-PLATE.

1,108,413.

Specification of Letters Patent. Patented Aug. 25, 1914.

Application filed January 23, 1914. Serial No. 813,914.

To all whom it may concern:

Be it known that I, JOHN F. WAIDELICH, a citizen of the United States of America, residing at Lansing, in the county of Ing-
ham and State of Michigan, have invented
certain new and useful Improvements in
Heel-Plates, of which the following is a
specification, reference being had therein to
the accompanying drawings.

- 10 My invention relates to heel plates and has among the objects thereof to provide an efficient heel plate that may be easily and cheaply manufactured; to provide a plate that may be readily applied to the heel; to
15 provide a heel plate in which the securing means is so arranged as to be protected from wear; and further to provide a heel plate that when secured in place on the heel, will not work loose.
- 20 The invention resides in the peculiar construction, arrangement and combinations of parts as will more fully hereinafter appear and as particularly pointed out in the claim.

In the drawings:—Figure 1 is a top plan view of the heel showing my improved heel plate applied thereto; Fig. 2 is a section on the line $\alpha-\alpha$ of Fig. 1; Fig. 3 is an enlarged perspective view of the heel plate looking from the top; and Fig. 4 is an enlarged central section through the heel plate.

A designates the heel of a shoe and B the heel plate embodying the invention. While the plate B may be of various configurations, it is preferably circular and centrally apertured, as designated by C, to receive the brad D or other securing means. The upper portion of the aperture C is of a size to receive the head E of the brad D, but adjacent the bottom the aperture C is of lesser size so as to form a shoulder F upon which the head E seats and which prevents the head of the brad from passing completely through the opening or aperture. With the particular construction of brad illustrated
45 the sides G of the head are beveled and the sides H of the seat are also beveled so as to fit the head and thereby avoid any tendency for play to occur between the head E and the seat F.

50 The top or exposed face I of the heel plate is flat but the bottom face is chambered, preferably an annular V-shaped chamber or groove J being formed therein. The edge

of the top face of the heel plate is beveled as indicated by K, to form a wedge, as will 55 more fully hereinafter appear.

In attaching the heel plate to the heel the latter is first chambered as by boring an opening L in the bottom of the heel, which is of a depth slightly less than the thickness 60 of the heel plate and of a width slightly less than the diameter or width of the heel plate. The heel plate is then forced or driven into the aperture L, the beveled edge K serving to form a wedge and also to guide 65 the plate into engagement with the aperture, the plate when arranged within the aperture L having the periphery thereof in tight contact with the sides of the bore L. The brad is then inserted in the aperture C 70 and driven into the heel, but as will be noted upon reference to Fig. 2 of the drawing, the head is considerably shorter than the depth of the upper portion of the aperture C, so that the top face M of the brad is positioned 75 below the outer face of the heel plate, which permits the latter to wear down without working off the head of the brad.

As will be seen from Fig. 2, when the heel plate is driven into the bore in the heel the 80 material of the heel will wedge itself into the V-shaped groove in the top face of the heel plate, since as before stated, the bore in the heel is of a depth slightly less than the thickness of the heel plate.

The construction heretofore described is one which may be easily and cheaply manufactured and that may be readily attached to the heel and when engaged with the heel, will not work loose.

85 What I claim as my invention is:—
A heel plate composed of a metallic member, provided with an aperture extending therethrough, the aperture being smaller adjacent the inner face of the member forming a shoulder or seat, said member being provided with an annular channel in its inner face surrounding said aperture, and the peripheral edge of the inner face being beveled, for the purpose described.

90 In testimony whereof I affix my signature in presence of two witnesses.

JOHN F. WAIDELICH.
